UNITED STATES PATENT OFFICE.

JONATHAN HALEY, OF AKRON, OHIO, ASSIGNOR TO THE AKRON GLASS AND MACHINERY COMPANY, OF AKRON, OHIO, A CORPORATION OF OHIO.

WARE-FEEDING APPARATUS FOR LEERS OR ANNEALING-FURNACES.

No. 800,645.

Specification of Letters Patent.

Patented Oct. 3, 1905.

Application filed July 18, 1904. Serial No. 217,074.

To all whom it may concern:

Be it known that I, JONATHAN HALEY, a citizen of the United States of America, residing at Akron, in the county of Summit and State 5 of Ohio, have invented certain new and useful Improvements in Ware-Feeding Apparatus for Leers or Annealing-Furnaces; and I hereby declare the following to be a full, clear and exact description of the invention, such 10 as will enable others skilled in the art to which it pertains to make and use the same.

This invention relates to improvements in apparatus for conveying glassware and other ware to be annealed into and through an annealing oven or chamber.

This invention pertains more especially to apparatus comprising an annealing-chamber open at its rear and ware-discharging end and heated by a heating-burner or heating appliance at its opposite and forward end and having a lateral doorway or inlet in one side wall thereof and near the said heating means for accommodating the passage of ware to be annealed into the said chamber and onto an endless conveyer arranged to bear the said ware longitudinally of and through the said chamber in the direction of the rear end of the chamber.

This invention chiefly comprises meritorious means for feeding the ware through the said inlet onto the aforesaid conveyer and for arranging the said ware in rows upon and transversely of the said conveyer, improved means for intermittently operating the said conveyer, and such a relative arrangement and operation of the parts of the apparatus that the members of each row of ware to be fed to and upon the said conveyer shall be successively delivered to the said conveyer in good condition and without injury to ware already delivered to the said conveyer and that the said conveyer shall upon the formation of each row of ware fed to the said conveyer be automatically actuated long enough to carry the said row of ware toward the rear and discharging end of the annealing-chamber and out of the way of the path of ware next fed onto the said conveyer in forming the next succeeding row of ware on the conveyer.

The object of this invention is to provide apparatus whereby the ware which is to be annealed is conveyed into and through the said chamber with facility and without liability of breakage of or injury to the ware.

With this object in view and to the end of 55 realizing other advantages hereinafter appearing this invention consists in certain features of construction and combinations of parts, hereinafter described, and pointed out in the claims.

In the accompanying drawings, Figure 1 is a top plan, partly in section, of a portion of an annealing oven or chamber and the greater portion of the apparatus embodying the said invention, and portions are broken 60 away in this figure to reduce the size of the drawing. Fig. 2 is a side elevation of the same, and portions are broken away and in section in this figure to reduce the size of the drawing and to more clearly show the construction. Fig. 3 is a top plan, in horizontal section, taken through the annealing-chamber, and portions are broken away in this figure to reduce the size of the drawing. Fig. 4 is a forward end elevation, largely in section, on line 44, Fig. 2. Fig. 5 is a top plan of a portion of the ware-feeding conveyer of the annealing-chamber. Fig. 6 is a section on line 66, Fig. 5, looking in the direction indicated by the arrow. Fig. 7 is a section on line 77, Fig. 6, looking in the direction indicated by the arrow. Fig. 8 is an elevation in section on line 88, Fig. 1, looking in the direction indicated by the arrow, and portions are broken away and in section in this figure to more 70 clearly show the construction. Fig. 9 is a rear side elevation in section on line 99, Fig. 8. Fig. 10 is a top plan of the crank-bearing portion of the crank-shaft F and shows the crank of the said shaft largely in section. Fig. 11 75 is a side elevation of the rear portion of the annealing-chamber-forming casing and shows, among other things, the ratchet-wheel and pawl instrumental in transmitting power to the conveyer of the said chamber. Fig. 12 is a top 80 plan in section of the inlet A' of the annealing-chamber and shows, among other things, the ware-receiving rack at the outer side of the said inlet. Fig. 13 is a side elevation in section on line 1313, Fig. 12, looking inwardly. Fig. 14 is a top plan of a portion of the apparatus, showing, among other things, means employed in transmitting and controlling the transmission of motion from the driving-shaft to the ware-feeding frame. Fig. 15 is a side elevation in section on line 1515, Fig. 14, looking inwardly. Fig. 16 is a vertical section on line 1616, Fig. 15, looking 85 90 95 100 105

rearwardly. Fig. 17 is a vertical section on line 17 17, Fig. 15, looking forwardly. Fig. 18 is a vertical section in detail on line 18 18, Fig. 4, looking in the direction indicated by 5 the arrow.

Figs. from 5 to 18, inclusive, are drawn on a larger scale than the first four figures.

Referring to the drawings, A designates the casing of an annealing oven or chamber 1,

10 which, as shown in Figs. 1, 3, and 4, is open at its rear and ware-discharging end. The chamber *a* is closed at its opposite end by suitably-applied doors *a'*, as shown in Fig. 1. One of the side walls of the casing A a short 15 distance rearward from the doors *a'* is provided (see Figs. 2, 3, and 4) with a lateral doorway or inlet *A'*, through which the ware which is to be annealed is fed into the chamber *a*.

20 Within the chamber *a* between the inlet *A'* and the doors *a'* are two gas-burners B, (see Figs. 1, 2, and 3,) arranged near opposite side walls, respectively, of the said chamber and connected in any approved manner and communicating with a gas-supply pipe *B'*, which is provided with a normally closed valve *B''*. The burners B are preferably so arranged relatively that the discharge-orifices *b* of each burner discharge opposite to and toward the 25 discharge-orifices of the other burner, so that the flames *b'* issuing from each burner during the operation of the burners will project toward the flames issuing from the other burner, as shown in Figs. 1 and 3. Heat is therefore supplied during the operation of the burners B to the chamber *a* at the ware-receiving or forward end portion of the said chamber between the inlet *A'* and the forward 30 extremity of the casing A.

35 The bottom of the chamber *a* is formed by an endless belt or conveyer which is arranged horizontally and extends longitudinally of the said chamber and, as shown in Figs. 2, 3, and 4, comprises two chains C and C, which are arranged a suitable distance apart widthwise of the chamber *a* and at the ware-discharging or rear end of the said chamber lead (see Fig. 3) over and operatively engage sprocket-wheels C', which are operatively mounted on 40 a shaft C'', arranged horizontally below and transversely of the said chamber. The said conveyer extends past the inlet *A'*, and the chains C at the ware-receiving or forward end portion of the chamber *a* lead over sprocket-wheels C'', arranged a suitable distance apart and mounted upon a shaft C', which is arranged horizontally below and transversely of the said chamber. (See Figs. 3 and 4.) The shafts C'' and C' are parallel and supported from the casing A, and the wheels of both pairs of sprocket-wheels C' and C'' are spaced apart correspondingly and arranged in line axially.

45 The chains C carry metal plates C⁵, which are arranged horizontally and extend trans-

versely and form the bottom of the chamber *a*. The plates C⁵ are attached to links of the chains C at the outer sides of the said chains. A portion of the chains C and attached plates C⁵ is shown very clearly in Figs. 5, 6, and 7. The plates C⁵ are secured by suitably-applied bolts C¹⁰ and nuts C¹⁰ to flanges C⁷ of arms C⁶, with which the links of the chains are provided.

50 Each plate C⁵ is wide enough to receive the article or ware to be annealed, and, as will hereinafter appear, the conveyer comprising the chains C and attached plates C⁵ is intermittently actuated; and the arrangement of the parts is such that the plates C⁵ of the said conveyer are successively brought into position to receive ware introduced into the forward end of the chamber *a* through the inlet A'.

55 A driving-shaft D (see Figs. 1 and 2) is arranged horizontally a suitable distance above and transversely of the chamber *a* and a suitable distance rearwardly of the path of the ware into the said chamber, being supported from standards A², resting upon and rigid with the casing A. The shaft D is provided 60 centrally between its ends with a driving-wheel D', to which power is suitably applied. The shaft D is provided near its end which is farther from the inlet A' (see Fig. 1) with a pinion D², loosely mounted on the said shaft. 65 The pinion D² meshes with a gear E², operatively mounted on a shaft E, which is parallel with and arranged centrally between the shaft D, and a crank-shaft F, arranged rearwardly of the shaft D. The shafts E and F are 70 arranged, therefore, horizontally and transversely of the chamber *a* and located above the casing A, being supported, respectively, from standards A³ and A⁴, which rest upon and are rigid with the casing A. The intermediate shaft E is operatively provided with a pinion E', which meshes with a gear F', operatively mounted on the shaft F. It will be observed, therefore, that power is transmitted to the shaft F from the shaft D upon establishing operative connection between the pinion D² and the said shaft D.

75 A clutch for controlling operative connection between the pinion D² and the shaft D is provided and comprises (see Figs. 8 and 9) 75 a member D⁴, slidably and operatively mounted on the shaft D, and a relatively stationary member D³, formed on the pinion D². The operative connection between the shaft D and the slideable clutch member D⁴ comprises, preferably, the well-known means of groove and feather, as at D⁶. It will be observed that the said clutch is arranged between the pinion D² and the driving-wheel D', and a collar D⁵, mounted on and fixed to the shaft D, is arranged as required to prevent displacement of the said pinion endwise of the shaft further from the slideable clutch member D⁴. The clutch member D⁴ is provided with an annular groove D⁷, which is engaged by the 80

roller R', with which a lever R is provided, which lever is applied and operated as will hereinafter appear.

The crank-shaft F projects a suitable distance beyond the ware-receiving side of the chamber a and is provided at the said side of the said chamber with a crank which is operatively connected with a rod G, which is arranged externally of the said chamber at 10 the said side of the said chamber between and engages the sheaves of any suitable number of corresponding pairs of guide-sheaves A⁵, which are supported from the casing A, as shown in Figs. 2 and 11, and guide the said rod. The rod G is shiftable endwise and extends toward and adjacent to the ware-discharging or rear end of the chamber a, and the operative connection provided between the said rod and the crank of the shaft F (see 15 Figs. 1 and 2) comprises, preferably, a pitman g, which is attached to the said rod a suitable distance rearward of the said shaft, and the connection between the said pitman and the rod G consists, preferably, of a collar 20 G', mounted on and adjustable endwise of the said rod and secured in the desired adjustment by a set-screw G². The pitman g is pivoted, as at g', to the collar G' horizontally and transversely of the rod G. The pitman 25 g extends from the collar G' upwardly in the direction of the ware-receiving end of the chamber a and at its upper end terminates in an eye g², which loosely embraces the wrist f² of the crank of the shaft F. The said 30 crank comprises a disk F², which is operatively mounted on the shaft F, and the wrist f², as shown very clearly in Fig. 10, is formed upon and projects laterally outwardly from a slide f, which engages and is adjustable end- 35 wise of a slideway-forming groove F³, which extends transversely and radially of the disk F² between and terminates a short distance from diametrically opposite points on the periphery of the said disk. Hence the groove 40 F³ has end walls F⁴, and a screw f' extends centrally and longitudinally of and through the said groove, and consequently through the slide f, and engages with corresponding screw-threads formed upon the surrounding wall of 45 the screw-engaging bore f³ of the said slide, which therefore constitutes a nut. The screw f' is stationary, so far as concerns endwise shifting of the screw when it is turned, extending loosely through the end walls F⁴ of 50 the groove F³ and having a head f⁴, arranged at the outer side of one of the said walls, and a correspondingly-threaded nut f⁵ engages the said screw at the outer side of the other of the said walls. It will be observed, therefore, that the stroke of the pitman g can be 55 shortened or lengthened by a proper readjustment of the slide f and collar G'. A pawl G³ (see Figs. 3 and 11) is pivoted at G¹ to the rear end of the rod G horizontally and transversely of the said rod and over

hangs and operatively engages a ratchet-wheel G⁵, which is operatively mounted on the shaft C².

It is obvious that the ware-feeding conveyer of the annealing-chamber is upon establishing operative connection between the pinion D² and the shaft D actuated in the direction required to convey any ware upon the conveyer toward the discharging or rear end of the said chamber and that the article or pieces of ware to be annealed are introduced through the inlet A' into the said chamber to and upon the said conveyer. Each plate C⁶ of the said conveyer has the dimensions required to accommodate a row of the said articles or pieces lengthwise of the plate and one article or piece widthwise of the plate. The said conveyer is actuated intermittently, being moved every time a plate C⁶ has been laden with a row of articles or pieces of ware far enough to remove the last-laden plate of the said conveyer from opposite the inlet A' toward the rear end of the chamber a and to bring the next succeeding and unladen plate C⁶ of the said conveyer opposite the said inlet and in position to receive ware fed into the said chamber through the said inlet. The arrangement of the parts is such therefore that a plate C⁶ of the said conveyer is always in position to receive ware fed into the chamber a at the inlet A'.

The casing A is provided at the bottom and outer side of the inlet A' (see Figs. 2, 3, 4, 12, and 13) with a rack h, which forms also the bottom of the said inlet and is arranged flush on top with or slightly above the upper or ware-receiving surface of the ware-carrying conveyer of the annealing-chamber a. The rack h is arranged and adapted to receive the ware to be annealed, one article or piece 100 at a time, preparatory to the passage of the said piece or article through the inlet A' into the chamber a and onto the said conveyer. The article or piece of ware to be annealed is delivered to and upon the rack h in any approved manner next to a stop-forming upright wall h', with which the said rack is provided adjacent to the rear side wall of the inlet A', whereupon the said piece or article is engaged upon its side opposite to the inlet A' by the 105 head H' of a rod H, which (see Figs. 2, 3, and 4) is arranged in line with the said inlet and horizontally and parallel with the ware-receiving plates C⁶ of the ware-carrying conveyer of the chamber a and extends outwardly from the 110 said head.

The rod H extends (see Fig. 4) through and is adjustable endwise of two boxes I and J, which afford bearing to the said rod and are rigid with and supported from a reciprocating frame arranged and adapted to travel transversely of the chamber a and in a line parallel with the ware-carrying plates C⁶ of the conveyer, which frame comprises, preferably, three parallel bars K', K², and K³, 115

120

125

130

which extend longitudinally of the said frame and are arranged at suitable intervals vertically above and parallel with the rod H. The said bars K', K², and K³ are rigidly secured 5 at their outer ends to a vertically-arranged bar or piece K. The outer box J is formed on the lower end of the upright bar K. The inner box I is formed by and upon the lower end of a depending arm K⁴, with which the inner 10 end of the lower bar K³ is provided. The said lower bar K³ is therefore shorter than the rod H and arranged near enough to the said rod to render it capable of passing, with the said rod, through the inlet A' during the operation 15 of the ware-feeding head H'. The rod H is adjustable longitudinally, as already indicated, and secured in the desired adjustment by a suitably-applied set-screw H², which extends into engagement with the said rod through a 20 correspondingly-threaded hole formed in the box J. It will be observed, therefore, that a loosening of the set-screw H² renders the ware-feeding head H' adjustable from and toward the ware-receiving rack h and enables an accurate 25 adjustment of the said head relative to the said rack preparatory to the operation of the ware-feeding frame comprising the said head, which frame is normally in its outer position, as shown in Fig. 4. The upper bar 30 K' and the central bar K² of the said frame form slides which engage correspondingly-arranged slideways L' and L², respectively, formed in and extending through an upright wall L, with which the top of the casing A is 35 provided. The wall L projects upwardly from and extends transversely of the casing A, and the bars K' and K² are long enough to extend a suitable distance along the engaging slideways in the outer and normal position of the 40 ware-feeding frame, so that the said frame is adequately supported in its said position. The arrangement of the parts is such that the head H' in the outer and normal position of the said frame is arranged directly opposite the 45 inlet A' and far enough from the said inlet to accommodate the passage of an article or piece of ware to be annealed onto the rack h between the said head and the said inlet. The said head H' has a concave face to render it 50 capable of partially embracing the article received upon the said head and to be removed by the said head from the rack h through the inlet A' into the chamber a, and obviously the said head and any article delivered in advance 55 thereof to and upon the said rack move toward and through the said inlet during the inward actuation of the aforesaid ware-feeding frame.

The central bar K² of the ware-feeding 60 frame is toothed upon its upper side to form a rack K⁵, which has a travel therefore within and endwise of the slideway L² during the reciprocation of the said frame, and moves transversely of and over the annealing chamber.

65 Arranged at right angles to the shaft D,

between the pulley D' and the inlet A' and between the said shaft and the path of the rack K⁵, (see Figs. 1, 14, and 15,) is a pinion-shaft k. The shaft k is arranged above and longitudinally of the chamber a and extends over 70 the path of the said rack. A pinion k² is operatively mounted upon the shaft k and meshes with the rack K⁵, as shown very clearly in Fig. 4. The pinion k² is arranged, therefore, within the wall L, which is slotted or cut away, 75 as at L³, to accommodate the location and operation of the said pinion. It will be observed, therefore, that the rack K⁵, and consequently the ware-feeding frame, are shifted endwise in the one or the other direction, according as the pinion-shaft is rotated in the one direction or the other, and obviously the ware-feeding device H' of the said frame is caused to remove any article upon the rack h through the inlet A' into the annealing-chamber according as the said frame is actuated in the one or the other direction.

Power is transmitted to the pinion-shaft k from the driving-shaft K, and the means employed in transmitting the said power comprises two corresponding oppositely-arranged bevel-gears d' and d², which (see Figs. 14 and 15) are loosely mounted on the said driving-shaft at opposite sides, respectively, of the pinion-shaft and mesh with a bevel-gear k', operatively mounted on the pinion-shaft between the gears d' and d². An endwise-shiftable sleeve d is operatively and slidably mounted upon the driving-shaft between the gears d' and d². The operative connection between the sleeve d and the driving-shaft comprises, preferably, the well-known means of groove and feather, as at d³. A clutch for controlling operative connection between the gear 90 d' and the shaft D is provided. One member d⁴ of this clutch is formed on the gear d', whereas the companion clutch member d⁵ is formed on the adjacent end of the sleeve d, and obviously the last-mentioned or movable 95 clutch member d⁵ is actuated into or out of operative engagement with the relatively stationary clutch member d⁴ according as the sleeve d is shifted endwise far enough in the direction of the said gear or moved away from 100 the gear. Another clutch for controlling operative connection between the gear d² and the shaft D is provided, and the movable member d⁷ of this clutch is formed on the sleeve d, whereas the relatively stationary member 105 d⁶ of the said clutch is formed on the said gear, and obviously the movable clutch member d⁷ is actuated into or out of operative engagement with the relatively stationary clutch member d⁶ according as the sleeve d is 110 shifted endwise far enough in the direction of the gear d² or moved away from the said gear. 115

In the normal position of the parts the sleeve d is in its central position, as shown in Figs. 14 and 16, centrally between the gears 120

d' and *d²*, which are arranged far enough apart to avoid establishing operative connection between them and the shaft *D* in the said central position of the sleeve *d*, and obviously 5 the clutch-controlling operative connection between the gear *d'* and the said shaft or the clutch-controlling operative connection between the said shaft and the gear *d²* is rendered operative according as the sleeve *d* is 10 actuated endwise far enough in the one or the other direction.

The means employed in actuating the sleeve *d* (see Figs. 1, 2, 14, 15, 16, and 17) comprises a lever *e*, which is arranged above and longitudinally of the chamber *a* and extends in under and transversely of the shaft *D*, being fulcrumed vertically, as at *e'*, to the top of the casing *A* between the shaft *D* and the shaft *E*. The lever *e* has a roller-bearing 20 arm *e'*, whose roller *e³* engages an annular groove *d⁸*, with which the sleeve *d* is externally provided. The lever *e* is provided with an arm *e⁴*, which projects from the fulcrum *e'* rearwardly. A lever *m* extends transversely of 25 the upper side of the arm *e⁴* and is fulcrumed horizontally at one end, as at *m'*, to the top of the casing *A* at one side of the said arm, and at the opposite side of the said arm is provided with a poise *m'*. The lever *m* is provided at 30 its under side with an inclined shoulder *m³*, which slopes upwardly in the direction in which the lever-arm *e⁴* moves during the actuation of the lever *e* in the direction required to shift the movable clutch member *d⁵* into 35 operative engagement with the companion clutch member *d⁴* in rendering the gear *d* operative. In the normal position of the parts, as already indicated, the lever *e* is in an intermediate position holding the sleeve *d* 40 in its intermediate position, wherein the clutch members carried by the said sleeve are out of operative engagement with the relatively stationary clutch members formed on the gears *d'* and *d²* and the lever-arm *e⁴* is in position 45 at the lower end of the incline *m³*, as shown very clearly in Figs. 14 and 16.

A slide *n* is arranged externally of the annealing-chamber and longitudinally of the ware-receiving side of the said chamber. The 50 slide *n* (see Figs. 2, 3, 12, and 13) engages a correspondingly-arranged slideway *A'*, with which the casing *A* is externally provided at and adjacent the bottom of the inlet *A'* between the said inlet and the rear end of the 55 annealing-chamber. The slide *n* is provided, at its rear end and beyond the rear end of the slideway *A'*, with a standard *n'*, which is provided with a rearwardly-projecting arm *n²*. (See Figs. 2, 3, and 14.) The casing *A* is provided, between the standard *n'* and the inlet *A'*, with an arm or bracket *A⁸*, which overlaps the outer side of the said standard and is provided with a guide-sheave *A⁹*. A cable *N*, by means of which a poise or weight *N'* is suspended, leads over the forward side and top 65

of the sheave *A⁹* to the rear end of the arm *n²*, to which the said cable is attached in any approved manner. The poise *N'* acts to retain the slide in its forward and normal position, wherein a stop—such, for instance, as the rear 70 side of the bracket *A⁸*—is engaged by the forward side edge of the standard *n'* and prevents forward movement of the slide beyond its forward and normal position. The lever *e* (see Figs. 2, 14, 15, and 17) has an arm *e⁵*, which projects in the direction of the path of the reciprocating ware-feeding frame and is normally engaged at its free end and at its side edge which faces the ware-receiving side of the annealing-chamber by the inner end of a 80 latch *l*, which is pivoted vertically centrally between its ends, as at *l'*, to the top of the casing *A*, and consequently capable of being swung in a horizontal plane. The latch *l* extends from the lever-arm *e⁵* in the direction of 85 the path of the slide *n*, and a suitably-applied spiral spring *l²* acts to retain the said latch in its normal position. The spring *l²* is shown attached at one end to the outer arm of the latch and at its opposite end to the upwardly-projecting wall *L* of the casing *A*. A vertically-tiltable dog *o* is pivoted horizontally, as at *o'*, to the outer end and longitudinally of the outer arm of the latch *l* and projects or depends from the latch in the direction of the 90 aforesaid ware-feeding frame. The dog *o* is free to swing upwardly, but rests below its axis upon the free end of the outer arm of the latch *l*, so that the latter is prevented from tilting downwardly. The standard *n'* is provided at its upper end with an arm *n³*, which projects forwardly in the direction of the path of the ware-feeding frame, and is provided at its free end with an upwardly-projecting member *n⁴*, arranged to bear rearwardly against 95 the forward side of the lower end of the dog *o*. 100

A plate *p*, which is preferably, but not necessarily, yieldable vertically, is (see Figs. 14, 15, and 17) supported from the arm *n³*, and preferably pivoted, as at *p'*, horizontally and transversely at the free end of and to the said arm. The plate *p* extends from the free end of the arm *n³* rearwardly and has an upwardly and rearwardly sloping upper side. A spiral spring *p²* is interposed between the under side 115 of the plate *p* and a laterally and outwardly projecting flange *n⁵*, with which the arm *n³* is provided, and acts to retain the said plate in its upper and normal position. The plate *p* is therefore capable of being depressed against 120 the action of the said spring *p²*, and is consequently yieldable vertically. The plate *p* is reduced in width toward its rear and free end, so that outer side edge of the said plate forms an incline *p³*, which extends from the rear and free end of the plate outwardly and forwardly. 125

A bar *Q*, arranged horizontally and transversely of the top of the casing *A*, (see Figs. 14, 15, and 17,) is pivoted vertically, as at *Q'*, to the arm *e⁵* of the lever *e* and extends later- 130

ally and outwardly from the said lever to and beyond the ware-receiving side of the annealing-chamber and overhangs and extends a suitable distance beyond the outer side of the 5 path of the slide n . The outer end portion of the bar Q is provided with two depending arms Q^2 and Q^3 , arranged a suitable distance apart longitudinally of the said bar. (See Fig. 17.) A slideway-forming rod Q^3 , which 10 is arranged below and longitudinally of the bar Q , extends between the lower ends of and is supported from the arms Q^2 . The arms Q^2 are provided also with a rod Q^5 , which is arranged parallel with the rod Q^3 and extends 15 loosely through and steadies the slide-forming collar M , which is slidably mounted on the rod Q^3 a suitable distance from the outer arm Q^2 and preferably next to the outer side of the inner arm Q^3 , and a spiral spring Q^4 is 20 mounted and confined upon the rod Q^3 between the outer end of the said collar or slide M and the outer arm Q^2 and acts to retain the said slide in its inner and normal position. The 25 slide M is provided with a depending member, which is preferably in the form of a vertically-arranged antifriction-roller M' , which in the normal position of the parts engages the inner and rear end of the incline p^3 . It will be observed, therefore, that during the 30 actuation of the slide n rearwardly the member n^4 of the said slide through the medium of the dog o renders the latch l inoperative by swinging the latter in the direction required to release the lever-arm e^5 , that while 35 the latch is being rendered inoperative the roller M' , and consequently the slide M , are, by means of the incline p^3 , actuated laterally and outwardly in the direction required to compress the spring Q^4 , and the arrangement 40 of the parts is such that the said spring shall not be fully compressed until the latch l has been rendered inoperative, whereupon a further actuation of the slide n in the same direction—namely, rearwardly—will result in 45 an outwardly endwise shifting of the bar Q , and thereby operate the lever e , as required, to shift the sleeve d in the direction of the path of the said slide and establish operative engagement between the members of the 50 clutch-controlling operative engagement between the driving-shaft D and the gear d' , and the spring Q^4 , having been compressed, operates to insure an adequate operative engagement of the clutch member d^5 with the 55 clutch member d^4 until the clutch member d^5 is again actuated out of engagement with the clutch member d^4 . During the said actuation of the said lever the arm e^2 of the lever moves in under and along the shoulder m^3 , so 60 as to enable the poise m^2 to facilitate the said actuation of the said lever and to retain the lever in position holding the clutch member d^5 in the proper engagement with the clutch member d^4 . 65 The driving-shaft D is rotated in the direc-

tion indicated by the arrow 24 in Figs. 14 and 15. The reciprocatory ware-feeding frame is normally arranged in its outer position, as already indicated, ready to remove an article or piece of ware delivered to and upon the rack 70 h through the inlet A' onto the ware-feeding conveyer of the annealing-chamber, and the arrangement of the parts is such that the establishment of operative connection between the gear d' and the shaft D will, through the 75 medium of the bevel-gear k' , pinion-shaft k , pinion k^2 , and a rack K^5 result in the inward actuation of the said frame.

It will be observed that operative connection between the gear d' and the driving-shaft 80 D is effected preparatory to each inward or ware-feeding movement of the ware-feeding frame and that the said operative connection must be interrupted and in lieu thereof operative connection established between the 85 gear d^2 and the said shaft preparatory to each return or reverse movement of the said frame; that the said frame in order to arrange the ware, which is fed by its ware-engaging device H' into the annealing-chamber in rows 90 upon and transversely of the ware-feeding conveyer of the said chamber must in feeding the first member of a row of ware be actuated the maximum distance, so as to move the said member of the row to be formed farther from 95 the inlet A' than the remaining and subsequently fed members of the said row and that the travel of the said frame during each subsequent ware-feeding movement thereof in the formation of the said row must be enough 100 shorter than the next preceding ware-feeding movement of the said frame to free the article or piece of ware next previously fed by the said frame, and consequently the shortest travel of the said frame will occur when the last member of the said row of ware is being 105 fed into the annealing-chamber. It is obvious, therefore, that the pinion-shaft k must be rotated longest without interruption during the feeding of ware to the annealing-chamber 110 when the first member of each row of ware to be formed on the ware-feeding conveyer of the said chamber is being fed into place on the said conveyer and that the said shaft during its intermittent rotation in feeding each 115 remaining member of the said row into place on the said conveyer must be rotated for an interval of time enough shorter than the time taken in having fed the next previously fed article or piece of ware to avoid collision with the last-mentioned piece or article on the said conveyer. 120

At the top and rear side of the travel of the ware-feeding and rack-bearing frame is a shaft T , which is arranged horizontally and transversely of the casing A and parallel with the said travel. The shaft T extends from end to end of the said frame. The shaft T (see Figs. 1, 2, 4, 14, 15, and 18) has bearing in two boxes K^7 and K^8 , with which the bar 130

K' of the said rack-bearing frame is provided, which boxes are arranged a suitable distance apart longitudinally of the said frame. The boxes K' and K'' are formed on brackets K'', which project laterally of the rack-bearing frame and rearwardly, and the wall L, at the rear of the slideway L', is slotted or recessed, as at L', (see Figs. 15 and 18,) to accommodate the location of the brackets K'' and avoid obstruction by the said brackets to the operation of the said frame.

The shaft T is provided at the inner end of the outer box K' with a collar secured to the said shaft in any approved manner. The shaft T is provided at its inner end with a collar T'', fixed to or formed on the shaft in any approved manner. It will be observed, therefore, that the shaft T is not only supported from the ware-feeding frame, but is prevented from endwise displacement independently of the said frame without interfering with the rotation of the shaft.

The shaft T is provided with as many laterally-projecting members t' as there are articles to be placed in a row within the annealing-chamber a, which members are spaced equidistantly longitudinally of the shaft as well as at equal intervals circumferentially of the shaft. In the machine illustrated the shaft 30 is provided with twelve projecting members t', and each member t' projects from and is rigid with a collar T', mounted on the shaft T and secured in the desired adjustment by a suitably-applied set-screw T', which is preferably countersunk in the said collar. The outermost member t' is formed by an annular flange with which the outermost collar T' is externally provided, and each remaining collar T' is formed by a pin inserted in and fixed 40 to the said collar in any approved manner. The outermost collar T' is one of the collars which participate in preventing endwise displacement of the shaft T.

The collar T' is shown fixed to the shaft T by a suitably-applied set-screw t'. The collar T' (and consequently the shaft T, of which the said collar forms a member) is provided with as many radially-arranged and laterally-projecting pins t' as there are projecting members 50 t' on the said shaft. The shaft T shown is provided, therefore, with twelve members t' spaced equally circumferentially of the collar T', and one of the said members t' is longer and projects farther from the shaft than the 55 remaining members t', as at 25.

A dog u is pivotally supported from the upper portion of the wall L of the casing A over the pinion k', being pivoted to the said wall, as at u', horizontally and longitudinally 60 of the casing A, and therefore arranged to swing in a vertical plane. The dog u projects in the direction in which the ware-feeding and shaft-bearing frame is actuated in feeding ware into the chamber a. The dog u over- 65 hangs the wall L and normally rests upon the

said wall and extends rearwardly beyond the rear side of the said wall. The dog u is provided at its rear side with an incline u'', which slopes rearwardly and toward the ware-receiving side of the chamber a and is arranged to 70 be engaged by a member t' of the shaft T during each outward or return movement of the ware-feeding frame. The under side of the dog u slopes, as at u', downwardly toward the free extremity of the dog, and the sloping 75 surface u'' is arranged in the path of a member t' of the shaft T during the inward or feeding movement of the ware-feeding frame.

The lever e is provided with another arm e', which projects into close proximity to the shaft T between the innermost member t' of the shaft T and an annular shoulder t'', formed on the said shaft by the inner end of the collar T''. The lever e' is arranged to be engaged by one of the projecting members t' of the 80 shaft T during each inward or feeding movement of the rack-bearing ware-feeding frame and is engaged by the shoulder t'' of the shaft T during each outward or return movement of the said frame.

The slide n is operated by pushing rearwardly against its forward end in any approved manner, and the arrangement of the parts is such that preparatory to the said operation of the said slide the ware-feeding 95 frame, and consequently the shaft T, are in their outer position and the lever e, as already indicated, in its intermediate position; that upon rendering the latch l inoperative, as hereinbefore described, the lever e is actuated 100 toward the ware-receiving side of the chamber a and operative connection is established between the gear d' and the driving-shaft D, and consequently between the rack K' and the said shaft, so that the ware-feeding frame 105 and its shaft T begin to move inwardly; that during the first inward stroke of the said frame the outermost projecting member t' of the shaft T shall come into engagement with the arm e' of the lever e and thereupon actuate the said lever to interrupt operative connection between the rack K' and the driving-shaft D and arrest the inward movement of the said frame when the article which is to be fed by the ware-feeding device of the said 110 frame during the said movement of the said frame has passed into the annealing-chamber and into place upon the conveyer of the said chamber; that a member t' of the shaft T shall pass in under and into engagement with 115 the sloping lower surface u' of the upwardly-swingable dog u during the said inward movement of the shaft T and result in idly swinging the said dog upwardly; that during the next succeeding outward or return stroke of 120 the ware-feeding frame the said member t' shall engage the incline u'' on the dog u and result in turning the shaft one-twelfth of a rotation and in the direction required to bring the second outermost projecting member t' of 125

130

the shaft T into position to actuate the lever e preparatory to and during the next inward stroke of the ware-feeding frame, and that the remaining members t^2 of the shaft T shall be operated in turn by the incline u^2 of the dog u, so as to oscillate the said shaft one-twelfth of a rotation during each outward or return stroke of the said frame, and thereby bring each projecting member t^3 of the shaft T in position in turn to actuate the aforesaid lever e. The collar T⁴, being secured to the shaft T by a set-screw, is consequently removable from the shaft upon loosening the said screw to accommodate the placing upon the said shaft of a collar having a less or greater number of radially-projecting members t^2 , as would be required in forming rows of ware upon the conveyer of a smaller or greater number than twelve. Obviously the projecting shaft members t^3 are rendered free to be adjusted longitudinally of the shaft T upon loosening the set-screws T⁴ of the collars T³, which when loosened can be removed from the shaft upon the removal of the collar T² to accommodate the arrangement upon the shaft of a smaller or larger number of collars T³, as would be required in reducing or enlarging the number of articles to be arranged in a row upon the conveyer. The shoulder t^6 of the shaft T is, as already indicated, arranged to engage the lever-arm e⁶ and thereupon actuate the lever e in the direction of the outer end of the travel of the ware-feeding frame during each return movement of the said frame, and the arrangement of the part is such that the lever-arm e⁶ upon the actuation of the lever e by the shoulder t^6 is disengaged by the said shoulder when the said lever has been actuated into its intermediate position, as shown in Fig. 14.

The twelfth operating member t^2 , which participates in the operation of the ware-feeding frame in returning the said frame to its outer and normal position next after feeding the last article of a row of articles onto the conveyer of the annealing-chamber, is somewhat longer—that is, projects farther from the shaft T, as at 25—than the remaining projecting member t^2 of the said shaft and has its outer end arranged to come into engagement during the said return movement of the said frame and before turning the said shaft during the said return movement of the said frame with a horizontally-swinging dog w, which is pivoted vertically, as at w', (see Figs. 1, 8, 9, and 15,) to a bar x, arranged above the casing A and resting upon a standard A¹⁰, with which the top of the said casing is provided. The bar x is arranged horizontally and transversely of said casing, and consequently longitudinally of the travel of the rack K⁵ of the ware-feeding frame. The dog w normally projects in the direction of the said travel.

The slidable member of the clutch controlling operative connection between the pinion D² and the driving-shaft D is provided with an annular groove D⁷, which, as already indicated, is shown in Figs. 1, 8, and 9 and is engaged by the roller R' of the lever R, which extends over and transversely of the said shaft, and consequently longitudinally of the casing A. The lever R is fulcrumed at its forward end, as at R², to the upper end of a standard or post A¹², with which the top of the casing A is provided between the driving-shaft and the travel of the ware-feeding frame. A suitably-applied torsional spring R³ is attached to the post or standard A¹² and acts to retain the lever R in position, holding the engaging clutch member D⁴ in operative engagement with the companion and relatively stationary clutch member D³, which spring, as shown in Figs. 1 and 8, has one end thereof overlapping the said lever near the fulcrum of the lever between the lever and the ware-receiving side of the annealing-chamber a.

The lever R extends to and over the intermediate shaft E and supports an endwise-shiftable rod r, which is arranged over and longitudinally of the lever R and has bearing in two boxes R⁴ and R⁵, with which the said lever is provided. The rod r extends through the outer or rear box R⁴ and at its rear end is provided with a head r', adapted to be engaged by a cam 26, with which the gear F' of the crank-shaft F is provided.

A sleeve y is slidably mounted on the rod r centrally between the boxes R⁴ and R⁵, and a spiral spring r² is mounted and confined on the said rod between the said sleeve and the inner box R⁵. The sleeve y is operatively connected by means of a link y' with the short arm of a bell-crank y², which is fulcrumed vertically to the upper end of the standard or post A¹², and preferably the axes of the levers R and y² are coincident. The short arm of the bell-crank y² projects in the direction of the pinion D², and the long arm of the said bell-crank projects in the direction of the travel of the ware-feeding frame and is vertically pivoted at its outer end, as at y³, to the adjacent end of the bar x, which is located between the driving-shaft and the travel of the ware-feeding frame and rests, as already indicated, upon the upper end of the standard A¹⁰. The bar x extends from the bell-crank y² toward the outer end of the ware-feeding frame and is held to the standard supporting it by a lug or pin 27 with which the said standard is provided and which projects upwardly from the standard into a diagonally-arranged slot x², formed in the said bar. The spring r² acts to retain the bell-crank y², and consequently the connected bar x, in their normal position. The bar x carries the dog w, as already indicated, and an upwardly-projecting lug or member

x' with which the said bar *x* is provided is arranged to prevent swinging of the said dog in the direction of the outer end of the travel of the ware-feeding frame. A suitably-applied 5 spiral spring *w*² acts to retain the dog *w* in its normal position, wherein the dog engages the aforesaid stop-forming member *x'* of the bar *x*. The spring *w*² is shown attached at one end to the rear end of a rearwardly-projecting arm *w*³ with which the dog *w* is provided and at its opposite end to and centrally between the ends of the bar *x*. Obviously the dog is free to swing in the direction in which the ware-feeding frame moves during the 15 ware-feeding movement of the said frame.

The arrangement of the parts is such that normally the cam 26 holds the clutch member *D*⁴, through the medium of the rod *r* and lever *R*, in its inoperative position against the 20 action of the spring *R*³; that the farther projecting member *t*² of the shaft *T* during the last feeding operation of the ware-bearing frame in feeding the last member of a row of ware to and upon the conveyer of the annealing-chamber idly swings the dog *w* in passing by the said dog; that the said member *t*² of the said shaft during the next outward or return movement of the said frame engages the opposite side of the said dog and thereupon 25 actuates the bar *x* in the direction of the outer end of the travel of the said frame and results in the actuation of the bell-crank *y*² in the direction required to pull upon the connected rod *r* in the direction of the said travel of 30 the said frame, and consequently to shift the said rod endwise against the action of the spring *r*² until the head *r'* of the said rod is disengaged from the cam 26 of the wheel *F*⁴ during the rotation of the said shaft subject 35 to the action of the spring *R*³, which thereupon actuates the lever *R* in the direction of the pinion *D*² and results in establishing operative connection between the said pinion and the shaft *D*, and consequently in the actuation of the aforesaid conveyer the distance 40 required to bring the next succeeding plate *C*⁵ of the said conveyer into position to receive ware fed into the annealing-chamber at the inlet of the said chamber.

45 As already indicated, the slot *x*² in the bar *x* is diagonally arranged, and consequently extends longitudinally as well as transversely of the bar, and the pin or projecting member 27 of the standard *A*¹⁰ normally engages the rear end of the said slot. Hence when the dog *w* is actuated in the direction of the ware-receiving side of the annealing-chamber by the outer end 25 of the longer pin or projecting member *t*² of the shaft *T* the bar *x* is actuated not only toward the ware-receiving side of the said chamber, but toward the rear end of the said chamber, and the arrangement of the parts and the length of the slot *x*² are such that the aforesaid member *t*² of the shaft 60 *T* during the operation of the bar *x* by the

said member *t*² shall release the dog *w* as soon as the head *r'* of the rod *r* is released from the cam 26, and the arrangement of the parts is such, furthermore, that the cam *r'*, having been disengaged by the head *r'* of the rod *r*, 70 again engages the said head and has again rendered the clutch member *D*⁴ inoperative upon the required actuation of the conveyer of the annealing-chamber.

As already indicated, the longer of the shaft 75 members *t*² is actuated to operate the bar *x* and connected mechanism during the last outward or return movement of the ware-feeding frame in forming a row of articles or ware upon the conveyer of the annealing-chamber and before the shaft *T* is turned during the said movement of the said frame, and Fig. 15 shows the shaft turned during the said movement of the said frame, and consequently shows the last operating and longer member 80 of the series of shaft members *t*² moved out of operative position relative to the dog *w*.

What I claim is—

1. The combination, with an annealing-chamber, and an endless conveyer arranged to 90 carry ware, which is to be annealed in the chamber, from within the forward and ware-receiving end of the chamber to the rear and discharging end of the chamber, of a ratchet-wheel operatively connected with the conveyer; a crank-shaft arranged externally and transversely of the annealing-chamber and located a suitable distance from the ratchet-wheel, which shaft has its crank provided with a slideway-forming radially-arranged groove 100 having end walls; a screw extending loosely through the said walls and arranged with its head at the outer side of one of the said walls; a correspondingly-threaded nut mounted on the screw at the outer side of the other of the 105 said walls; a slide-forming nut mounted on and operatively engaging the screw and provided with the wrist of the crank; means for intermittently rotating the shaft; an endwise-shiftable rod arranged at one side and externally of the annealing-chamber and extending longitudinally of the chamber between the shaft and the ratchet-wheel; a pawl pivotally supported from the rod and operatively engaging the ratchet-wheel; a collar embracing 115 and adjustably endwise of the rod; means for securing the collar in the desired adjustment; a pitman terminating at one end in an eye embracing the crank-wrist and operatively attached at its other end to the collar, and means 120 for guiding the rod.

2. The combination, with an annealing-chamber, and an endless conveyer arranged to 125 carry ware, which is to be annealed in the chamber, from within the forward and ware-receiving end of the chamber to the rear and discharging end of the chamber, of a ratchet-wheel operatively connected with the conveyer; a crank-shaft arranged externally and transversely of the annealing-chamber and lo- 130

cated a suitable distance from the ratchet-wheel, which shaft has its crank provided with a slideway-forming radially-arranged groove having end walls; a screw extending loosely through the said walls and stationary so far as endwise movement during its rotation is concerned; a slide-forming nut mounted on and operatively engaging the screw and provided with the wrist of the crank; means for intermittently rotating the shaft; an endwise-shiftable rod arranged at one side and externally of the annealing-chamber and extending longitudinally of the chamber between the shaft and the ratchet-wheel; a pawl pivotally supported from the rod and operatively engaging the ratchet-wheel; a collar embracing and adjustable endwise of the rod; means for securing the collar in the desired adjustment; a pitman establishing operative connection between the crank-wrist and the collar, and means for guiding the rod.

3. The combination, with an annealing-chamber, and an endless conveyer arranged to carry ware, which is to be annealed in the chamber, from within the forward and ware-receiving end to the rear and discharging end of the chamber, of a ratchet-wheel operatively connected with the conveyer; a crank-shaft arranged externally and transversely of the annealing-chamber and located a suitable distance from the ratchet-wheel, which shaft has its crank provided with a radially-arranged slideway; a screw arranged within and extending longitudinally of the slideway and stationary so far as endwise movement during its rotation is concerned; a slide-forming nut mounted on and operatively engaging the screw and provided with the wrist of the crank; means for intermittently rotating the shaft; an endwise-shiftable rod arranged at one side and externally and longitudinally of the annealing-chamber between the shaft and the ratchet-wheel, which rod is operatively connected at one end with the crank-wrist; a pawl pivotally supported from the opposite end of the rod and operatively engaging the ratchet-wheel, and means for guiding the rod.

4. The combination, with an annealing-chamber, and an endless conveyer arranged to carry ware, which is to be annealed in the chamber, from within the forward and ware-receiving end to the rear and discharging end of the chamber, of a ratchet-wheel operatively connected with the conveyer; an endwise-shiftable rod arranged externally of the annealing-chamber; a pawl pivotally supported from the rod and operatively engaging the ratchet-wheel; means for actuating the rod, and means whereby the length of the stroke of the rod can be changed.

5. The combination, with an annealing-chamber provided, in one of its side walls and near one end, with a lateral ware-receiving inlet and discharging at its opposite end, and an endless conveyer arranged to carry ware,

which is to be annealed in the said chamber, from within the forward and ware-receiving end to the rear and discharging end of the chamber, of a ratchet-wheel operatively connected with the conveyer at the rear end of the chamber, a driving-shaft arranged above and transversely of the annealing-chamber between opposite ends of the chamber and a suitable distance from the rear end of the chamber, a crank-shaft arranged above the chamber parallel with the driving-shaft and located between the driving-shaft and the rear end of the chamber, a pinion loosely mounted on the driving-shaft and intergeared with the crank-shaft, a clutch for establishing and interrupting operative connection between the pinion and the driving-shaft, an endwise-shiftable rod arranged at one side and externally of the annealing-chamber and extending longitudinally of the said chamber between the crank-shaft and the ratchet-wheel, a pitman establishing operative connection between the said rod and the wrist of the crank of the crank-shaft, guide-sheaves arranged at suitable intervals longitudinally of the upper side of and engaging the rod, and other guide-sheaves arranged at suitable intervals longitudinally of the lower side of and engaging the rod.

6. The combination, with an annealing-chamber provided, in one of its side walls and near one end, with a lateral ware-receiving inlet and discharging at its opposite end, and an endless conveyer arranged to carry ware, which is to be annealed in the said chamber, from within the forward and ware-receiving end to the rear and discharging end of the chamber, of a ratchet-wheel operatively connected with the conveyer at the rear end of the chamber, a driving-shaft arranged transversely of the chamber between opposite ends of the chamber and a suitable distance from the rear end of the chamber, a crank-shaft arranged parallel with the driving-shaft and located between the driving-shaft and the rear end of the chamber, a pinion loosely mounted on the driving-shaft and intergeared with the crank-shaft, a clutch for establishing and interrupting operative connection between the pinion and the driving-shaft, an endwise-shiftable rod arranged at one side and externally of the annealing-chamber and extending longitudinally of the said chamber between the crank-shaft and the ratchet-wheel, a pawl pivoted horizontally to and transversely of the rear end of the rod and operatively engaging the ratchet-wheel, a pitman establishing operative connection between the rod and the wrist of the crank of the crank-shaft, and means for guiding the rod.

7. The combination, with an annealing-chamber provided, in one of its side walls and near one end, with a lateral ware-receiving inlet and discharging at its opposite end, and an

endless conveyer arranged to carry ware, which is to be annealed in the said chamber, from within the forward and ware-receiving end to the rear and discharging end of the chamber, of a ratchet-wheel operatively connected with the said conveyer, a crank-shaft arranged externally and transversely of the said chamber, means for intermittently operating the crank-shaft, an endwise-shiftable rod arranged at one side and longitudinally of the annealing-chamber, a pawl pivoted horizontally to and transversely of the said rod and overhanging and operatively engaging the ratchet-wheel, a pitman establishing operative connection between the rod and the wrist of the crank of the crank-shaft, and means for guiding the rod.

8. The combination, with an annealing-chamber and an endless conveyer arranged to carry ware, which is to be annealed in the said chamber, from within the forward and ware-receiving end to the rear and discharging end of the chamber, of a ratchet-wheel operatively connected with the said conveyer; a driving-shaft; a crank-shaft; a pinion loosely mounted on the driving-shaft and intergeared with the crank-shaft; a clutch for establishing and interrupting operative connection between the pinion and the driving-shaft; a pawl operatively engaging the ratchet-wheel, and a pitman operatively connected, at one end, with the pawl and, at its opposite end, with the wrist of the crank of the crank-shaft.

9. The combination, with an interiorly-chambered casing which forms an annealing-chamber provided with a ware-receiving inlet; a conveyer arranged to carry ware, which is to be annealed in the chamber, from adjacent the said inlet through the chamber; means for actuating the conveyer, and a seat arranged at the outer side of and at the bottom of the aforesaid inlet, of a suitably-supported reciprocatory frame provided with a device arranged to engage an article placed on the said seat and feed the said article through the said inlet into the annealing-chamber and onto the aforesaid conveyer, which frame is provided with a rack arranged longitudinally of the frame; a driving-shaft arranged parallel with the travel of the rack; a pinion-shaft arranged between the said travel and the driving-shaft; the pinion operatively mounted on the pinion-shaft and meshing with the rack; two oppositely-arranged bevel-gears loosely mounted on the driving-shaft at opposite sides respectively of the pinion-shaft; two suitably-operated clutches for controlling operative connection between the sleeve and the different driving-shaft gears respectively and the driving-shaft, and a bevel-gear operatively mounted on the pinion-shaft and meshing with both of the gears on the driving-shaft.

10. The combination, with an interiorly-chambered casing which forms an annealing-chamber provided in one of its side walls and

near one end with a lateral inlet and discharging at its opposite end; a conveyer arranged to carry ware, which is to be annealed in the chamber, from within the forward and ware-receiving end to the rear and discharging end of the chamber; means for actuating the conveyer, and a seat arranged at the outer side of and at the bottom of the aforesaid inlet, of a reciprocatory frame provided with a device arranged to engage an article placed on the said seat and feed the said article through the said inlet into the annealing-chamber and onto the aforesaid conveyer, which frame is supported from the aforesaid casing and provided with a rack arranged transversely of the said casing; a driving-shaft arranged parallel with the travel of the rack; a pinion-shaft arranged between the said travel and the driving-shaft; the pinion operatively mounted on the pinion-shaft and meshing with the rack; two oppositely-arranged bevel-gears loosely mounted on the driving-shaft at opposite sides respectively of the pinion-shaft; two suitably-operated clutches for controlling operative connection between the sleeve and the different driving-shaft gears respectively and the driving-shaft, and a bevel-gear operatively mounted on the pinion-shaft and meshing with both of the gears on the driving-shaft.

11. The combination, with an interiorly-chambered casing which forms an annealing-chamber provided, in one of its side walls and near one end, with a lateral inlet and discharging at its opposite end; a conveyer arranged to carry ware, which is to be annealed in the chamber, from within the forward and ware-receiving end to the rear and discharging end of the chamber; means for actuating the conveyer, and a seat arranged at the outer side of and at the bottom of the aforesaid inlet, of a reciprocatory frame provided with a device arranged to engage an article placed on the said seat and feed the said article through the said inlet into the annealing-chamber and onto the aforesaid conveyer, which frame is supported from the aforesaid casing and provided with a rack arranged transversely of the said casing; a driving-shaft; a pinion-shaft operatively connected with the rack; two oppositely-arranged bevel-gears loosely mounted on the driving-shaft at opposite sides respectively of the pinion-shaft, and two suitably-operated clutches for controlling operative connection between the different driving-shaft gears respectively and the shaft, and means for actuating the sleeve.

12. The combination, with an interiorly-chambered casing which forms an annealing-chamber provided, in one of its side walls and near one end, with a lateral inlet and discharging at its opposite end; a conveyer arranged to carry ware, which is to be annealed in the said chamber, from within the forward and ware-receiving end to the rear and discharging end of the chamber; means for actuating the

conveyer, and a seat arranged at the outer side of and at the bottom of the aforesaid inlet, of a reciprocating frame provided with a device arranged to engage an article placed 5 on the said seat and feed the said article through the aforesaid inlet into the annealing-chamber and onto the aforesaid conveyer, which frame is supported from the aforesaid casing and is provided with a rack arranged horizontally 10 and transversely of the said casing; a driving-shaft; a pinion-shaft arranged at a right angle to the travel of the rack-bearing frame; the pinion operatively mounted on the pinion-shaft and meshing with the rack; two gears 15 loosely mounted on the driving-shaft and operatively connected with the pinion-shaft; a clutch controlling operative connection between the driving-shaft and one of the said gears, and another clutch controlling operative 20 connection between the driving-shaft and the other of the said gears.

13. The combination, with an interiorly-chambered casing which forms an annealing-chamber provided, in one of its side walls and 25 near one end, with a lateral inlet and discharging at its opposite end, and a conveyer arranged to carry ware, which is to be annealed in the said chamber, from within the forward and ware-receiving end to the rear and discharging end of the chamber, and means for operating the said conveyer, of a suitably-supported reciprocating frame instrumental in feeding ware through the aforesaid inlet into the annealing-chamber and onto the aforesaid conveyer; a driving-shaft; two oppositely-arranged bevel-gears loosely mounted on the driving-shaft; such an operative connection 30 between the said gears and the ware-feeding frame that the latter is actuated in the one or 35 the other direction according as operative connection is established between the one or the other of the gears and the shaft; a clutch controlling operative connection between the shaft and one of the gears, and another clutch 40 controlling operative connection between the 45 shaft and the other gear.

14. The combination, with an interiorly-chambered casing which forms an annealing-chamber provided, in one of its side walls and 50 near one end, with a lateral inlet and discharging at its opposite end; a conveyer arranged to carry ware, which is to be annealed in the said chamber, from within the forward and ware-receiving end to the rear and discharging end of the chamber, and means for actuating the said conveyer, of a reciprocating frame instrumental in feeding ware through the aforesaid inlet into the annealing-chamber and onto the aforesaid conveyer, which frame 55 is supported from the aforesaid casing and is provided with a rack arranged horizontally and transversely of the said casing; a pinion meshing with the said rack and means for rotating the said pinion in opposite directions 60 alternately.

15. The combination, with an interiorly-chambered casing which forms an annealing-chamber provided with a ware-receiving inlet at its forward end; a conveyer arranged to carry ware, which is to be annealed in the said chamber, from within the forward and ware-receiving end to the rear and discharging end of the chamber, and means for actuating the said conveyer, of a device instrumental in feeding ware through the aforesaid inlet into the annealing-chamber and onto the aforesaid conveyer, and mechanism for operating the said ware-feeding device, which mechanism comprises a rack connected to the ware-feeding device, and a pinion meshing with the rack, 75 and means for rotating the pinion.

16. The combination, with an interiorly-chambered casing which forms an annealing-chamber provided, in one of its side walls and 80 near one end, with a lateral inlet and discharging at its opposite end, a conveyer arranged to carry ware, which is to be annealed in the said chamber, from within the forward and ware-receiving end to the rear and discharging end of the chamber, and means for operating the said conveyer, of a rack or seat arranged at the bottom and outer side of the aforesaid inlet; a horizontal rod arranged in line with and normally outside of the said inlet and provided, at its inner end, with a head 85 arranged to engage an article placed on the aforesaid seat at the side farthest from the aforesaid inlet and feed the said article through the said inlet into the annealing-chamber and onto the aforesaid conveyer; a reciprocating frame carrying the said rod and comprising three horizontal bars parallel with and above the rod and arranged at suitable intervals vertically and an upright bar connecting together 90 and secured to the said horizontal bars at the outer end of the rod and affording bearing to the rod, with the lower bar low enough to enter the aforesaid aperture and provided with a depending arm affording bearing to the rod, and with the central and upper bars forming 95 slides and extending inwardly beyond the ware-feeding head of the rod; a stationary wall projecting upwardly from the aforesaid casing and provided interiorly with slideways 100 engaged by the slide-forming bars, and means 105 for actuating the aforesaid frame.

17. The combination, with an interiorly-chambered casing which forms an annealing-chamber provided with an inlet; a conveyer arranged to carry ware, which is to be annealed in the said chamber, from adjacent the said inlet to the rear and discharging end of the chamber, and means for actuating the conveyer, of a suitably-supported ware-feeding device instrumental in feeding ware through 110 the aforesaid inlet into the annealing-chamber and onto the aforesaid conveyer; a driving-shaft; two oppositely-arranged bevel-gears loosely mounted on the driving-shaft; such an operative connection between the said gears 115 120 125 130

- and the ware-feeding device that the latter is actuated in the one or the other direction according as operative connection is established between the one or the other of the gears 5 and the shaft; a clutch controlling operative connection between the shaft and one of the gears, and another clutch controlling operative connection between the shaft and the other gear.
18. The combination, with an interiorly-chambered casing which forms an annealing-chamber provided, in one of its side walls and near one end, with a lateral inlet and discharging at its opposite end; a conveyer arranged to carry ware, which is to be annealed in the said chamber, from within the forward and ware-receiving end to the rear and discharging end of the chamber; and means for actuating the said conveyer, of a reciprocatory frame provided with a device arranged to feed ware through the aforesaid inlet into the annealing-chamber and onto the aforesaid conveyer, which frame has a slide-forming member extending inwardly beyond the aforesaid ware-feeding device; a slideway for the said slide-forming member, and means for actuating the aforesaid frame.
19. The combination, with an annealing-chamber having an inlet, and the conveyer 30 for carrying ware in the said chamber, of a ware-feeding frame provided with a member arranged to feed ware through the aforesaid inlet into the annealing-chamber and onto the aforesaid conveyer; means for actuating the said frame; a shaft arranged longitudinally of and supported from the said frame, which shaft is provided with a series of laterally-projecting members spaced longitudinally and circumferentially of the shaft and successively instrumental in the interruption of the operation of the aforesaid frame-actuating means to limit the ware-feeding movement of the said frame, and means for turning the shaft, during the movement of the ware-feeding frame in the opposite direction, far enough to bring the next succeeding member of the aforesaid series of projecting members of the shaft into position for operation substantially as and for the purpose set forth.
20. The combination, with an annealing-chamber having an inlet, and the conveyer for carrying ware in the chamber, of a ware-feeding frame provided with a member arranged to feed ware through the aforesaid inlet into the annealing-chamber and onto the conveyer; means for actuating the said frame; a shaft arranged longitudinally of and supported from the frame, which shaft is provided with a series of laterally-projecting members adjustable longitudinally of the shaft and spaced longitudinally and circumferentially of the shaft and arranged to be successively instrumental in interrupting the operation of the frame-actuating means to limit the ware-feeding movement of the frame,
- and means for turning the shaft, during the movement of the ware-feeding frame in the opposite direction, far enough to bring the next succeeding member of the aforesaid series of projecting members of the shaft into position for operation, substantially as and for the purpose set forth.
21. The combination, with an annealing-chamber having an inlet, and the conveyer for carrying ware in the said chamber, of a ware-feeding frame provided with a member arranged to feed ware through the aforesaid inlet into the annealing-chamber and onto the aforesaid conveyer; means for actuating the said frame; a shaft arranged longitudinally of and supported from the said frame, which shaft is provided with a series of laterally-projecting members spaced longitudinally and circumferentially of the shaft and arranged to be successively instrumental in interrupting the operation of the aforesaid frame-actuating means to limit the ware-feeding movement of the said frame, which shaft has another member instrumental in interrupting the operation of the frame-actuating means to limit the movement of the said frame in the opposite direction, and means for turning the shaft, during the last-mentioned movement of the ware-feeding frame, far enough to bring the next succeeding member of the aforesaid series of projecting members of the said shaft into position for operation, substantially as and for the purpose set forth.
22. The combination, with an annealing-chamber having an inlet, and the conveyer for carrying ware in the said chamber, of a ware-feeding frame provided with a member arranged to feed ware through the aforesaid inlet into the annealing-chamber and onto the aforesaid conveyer; means for actuating the said frame; a shaft arranged longitudinally of and supported from the said frame, which shaft is provided with a series of laterally-projecting members spaced longitudinally and circumferentially of the shaft and arranged to be successively instrumental in interrupting the operation of the aforesaid frame-actuating means to limit the ware-feeding movement of the said frame; means for preventing endwise displacement of the shaft, and means for turning the shaft, during the movement of the ware-feeding frame in the opposite direction, far enough to bring the next succeeding member of the aforesaid series of projecting members of the said shaft into position for operation.
23. The combination, with an annealing-chamber provided with a ware-receiving inlet; a conveyer arranged to carry ware in the said chamber, and means for actuating the conveyer, of a reciprocatory frame provided with a device arranged to feed ware through the aforesaid inlet into the annealing-chamber and onto the aforesaid conveyer during the inward or ware-feeding movement of the

frame; a driving-shaft; two gears loosely mounted on the driving-shaft a suitable distance apart; such an operative connection between the gears and the ware-feeding frame 5 as to move the frame in the one direction or the other according as operative connection between the one or the other of the gears and the shaft is established; a sleeve slidably and operatively mounted on the shaft between the 10 gears and normally in its intermediate position; two clutches arranged at opposite ends respectively of the sleeve and controlling operative connection between the sleeve and the different gears, respectively, and each 15 clutch having its two component members rigid with the sleeve and adjacent gear respectively; a lever operatively engaging the sleeve; means for actuating the said lever in the direction and to the extent required to 20 operate one of the clutches and thereby effect the inward and ware-feeding movement of the ware-feeding frame, and means for actuating the lever in the opposite direction to the extent required to operate the other clutch and 25 thereby effect the movement of the said frame in the opposite direction.

24. The combination, with an annealing-chamber having an inlet; the conveyer for carrying ware in the said chamber; a suitably-supported ware-feeding frame having a 30 member arranged to feed ware through the aforesaid inlet onto the aforesaid conveyer, and means for actuating the said frame, of a shaft arranged longitudinally of and supported from the said frame and provided with a series of laterally-projecting members spaced longitudinally and circumferentially of the shaft and arranged to be successively instrumental in interrupting the 35 operation of the aforesaid frame-actuating means to limit the ware-feeding movement of the frame, which shaft has another series of laterally-projecting members instrumental in turning the shaft and arranged to operate 40 successively and corresponding in number and arrangement circumferentially of the shaft to the first-mentioned series of shaft members, and means for engaging a member of the second-mentioned series of shaft members 45 between successive ware-feeding movements of the ware-feeding frame and thereby turning the shaft far enough to bring the next succeeding member of the said series of shaft members in position for operation.

55. 25. The combination, with an annealing-chamber having an inlet; the conveyer for carrying ware in the said chamber; a ware-feeding frame having a member arranged to feed ware through the aforesaid inlet onto 60 the aforesaid conveyer, and means for actuating the said frame, of a shaft arranged longitudinally of and supported from the said frame and provided with a series of laterally-projecting members suitably spaced longitudinally and circumferentially of the shaft

and arranged to be successively instrumental in interrupting the operation of the aforesaid frame-actuating means to limit the ware-feeding movement of the said frame, which shaft has another series of projecting members instrumental in turning the shaft and arranged to operate successively and corresponding in number and arrangement circumferentially of the shaft to the first-mentioned series of shaft members, and means whereby a member of the second-mentioned series of shaft members is engaged and actuated to turn the shaft to bring the next succeeding member of the said series of shaft members in position for operation during each return movement of the ware-feeding frame. 70 75 8c

26. The combination, with an annealing-chamber having an inlet; a conveyer for carrying ware in the said chamber; a ware-feeding frame having a member arranged to feed ware through the aforesaid inlet onto the aforesaid conveyer, and means for actuating the said frame, of a shaft arranged longitudinally of and supported from the said frame and provided with a series of laterally-projecting members spaced longitudinally and circumferentially of the shaft and arranged to be successively instrumental in interrupting the operation of the aforesaid frame-actuating means to limit the ware-feeding movement of the said frame, and means whereby the shaft is turned far enough between successive ware-feeding movements of the ware-feeding frame to bring the next succeeding member of the said series of shaft members 90 95 100 in position for operation.

27. The combination, with an annealing-chamber having an inlet; a conveyer for carrying ware in the said chamber; of a ware-feeding frame having a member arranged to feed ware through the aforesaid inlet onto the aforesaid conveyer; means for actuating the said frame; a driving-shaft; a pinion loosely mounted on the said shaft; means for transmitting motion from the pinion to the aforesaid conveyer; a shaft arranged longitudinally of and supported from the ware-feeding frame, which shaft is provided with a series of laterally-projecting members instrumental in turning the shaft and arranged to operate 105 successively, with one of the said shaft members projecting farther from the axis of the shaft than the remaining members of the said series of shaft members, and means whereby a member of the said series of shaft members 110 is engaged and actuated to turn the shaft to bring the next succeeding member of the said series of shaft members in position for operation between successive ware-feeding movements of the ware-feeding frame, of a sleeve 115 slidably and operatively mounted on the driving-shaft adjacent the pinion; a clutch arranged to establish operative connection between the pinion and the driving-shaft and having its two component members on the 120 125 130

sleeve and pinion respectively; means acting to retain the sleeve in position with the movable clutch member in operative engagement with the companion clutch member; mechanism for actuating the sleeve to render the movable clutch member inoperative, and means adapted to render the last-mentioned mechanism inoperative and arranged to be operated by the outer end of the longer member of the aforesaid series of projecting shaft members, all arranged and timed to operate substantially as and for the purpose set forth.

28. The combination, with an annealing-chamber having an inlet; a conveyer for carrying ware in the said chamber; means for feeding ware through the aforesaid inlet onto the aforesaid conveyer and arranging the ware in rows upon the conveyer; a driving-shaft; a pinion loosely mounted on the said shaft; means for transmitting motion from the pinion to the aforesaid conveyer; a clutch for controlling operative connection between the pinion and the shaft; means acting to operate the clutch; mechanism for rendering the clutch inoperative, and means arranged to render the last-mentioned mechanism inoperative and timed to operate between the formation of one row of ware on the aforesaid conveyer and the beginning of the formation of the next succeeding row of ware on the said conveyer.

29. The combination, with an annealing-chamber having an inlet; a conveyer for carrying ware in the said chamber; means for feeding ware through the aforesaid inlet onto the aforesaid conveyer; a driving-shaft; a pinion loosely mounted on the said shaft, and means for transmitting motion from the pinion to the aforesaid conveyer, of a sleeve slidably and operatively mounted on the shaft adjacent the pinion; a clutch arranged to establish operative connection between the pinion and the driving-shaft and having its two component members on the sleeve and pinion respectively; means acting to retain the sleeve in position with the movable clutch member in operative engagement with the relatively stationary clutch member; mechanism for actuating the sleeve to render the movable clutch member inoperative, and means arranged to render the last-mentioned mechanism inoperative and timed to operate between the formation of one row of ware on the aforesaid conveyer and the beginning of the formation of the next succeeding row of ware on the said conveyer.

30. The combination, with an annealing-chamber provided with a ware-receiving inlet; a conveyer arranged to carry ware in the said chamber, and means for actuating the said conveyer; a ware-feeding device arranged to feed ware through the aforesaid inlet into the annealing-chamber and onto the aforesaid conveyer; a driving-shaft; means for actuating the ware-feeding device to effect its ware-

feeding movement, which means comprises a gear loosely mounted on the driving-shaft; a clutch controlling operative connection between the said gear and the shaft, with the clutch normally inoperative, and the clutch-operating lever, of a latch normally in position to prevent the clutch-lever from moving to operate the clutch; means acting to retain the latch in its normal and operative position; means for rendering the latch inoperative; an endwise-shiftable bar connected with the lever and extending from the lever in the direction in which the said lever is moved in operating the clutch, which bar is provided with two arms arranged a suitable distance apart longitudinally of and depending from the bar; a slideway-forming rod extending between and supported from the said arms; a slide mounted on and shiftable endwise of the said rod between the arms; an upright roller carried at the under side of and by the said slide and the outer arm of the bar; a suitably-supported slide movable longitudinally of the annealing-chamber and provided with an arm arranged to operate the means employed in rendering the latch inoperative, and an incline carried by the last-mentioned slide and arranged to be engaged by the aforesaid roller, all arranged and timed to be operated substantially as and for the purpose set forth.

31. The combination, with an annealing-chamber provided with a ware-receiving inlet; a conveyer arranged to carry ware in the said chamber, and means for actuating the said conveyer; a ware-feeding device arranged to feed ware through the aforesaid inlet into the annealing-chamber and onto the aforesaid conveyer; a driving-shaft; means for actuating the ware-feeding device to effect its ware-feeding movement, which means comprises a gear loosely mounted on the driving-shaft; a clutch controlling operative connection between the said gear and the shaft, with the clutch normally inoperative, and the clutch-operating lever, of an endwise-shiftable bar connected with the lever and extending from the lever in the direction in which the said lever is moved in operating the clutch; a slide supported from and movable endwise of the said bar and normally in its inner position; a roller borne by the said slide; a spring acting to retain the said slide in its normal position and confined at the outer end of the slide, and means arranged to engage the said roller and thereby actuate the slide outwardly against the action of the spring and result in the actuation of the aforesaid lever to operate the clutch.

In testimony whereof I sign the foregoing specification in the presence of two witnesses.

JONATHAN HALEY.
